United States Patent [19]

Kagayama et al.

[11] Patent Number: Des. 300,637

[45] Date of Patent: ** Apr. 11, 1989

[54] CARTESIAN COORDINATES TYPE ROBOT

[75] Inventors: Katsuji Kagayama, Nara; Benito Mishiro; Ikuo Nishimura, both of Osaka, all of Japan

[73] Assignee: Matsushita Electric Industrial Co., Ltd., Osaka, Japan

[**] Term: 14 Years

[21] Appl. No.: 905,109

[22] Filed: Sep. 8, 1986

[30] Foreign Application Priority Data

Apr. 22, 1986 [JP] Japan 61-15007

[52] U.S. Cl. D15/199; D15/122

[58] Field of Search D15/122, 199; 414/749, 414/750; 901/16

[57] CLAIM

The ornamental design for a cartesian coordinates type robot, as shown.

DESCRIPTION

FIG. 1 is a front, top and right side perspective view of a cartesian coordinates type robot showing our new design;

FIG. 2 is a rear, bottom and left side perspective view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a right side elevational view thereof; and

FIG. 8 is a left side elevational view thereof.
